US0D1057997S

(12) **United States Design Patent** (10) **Patent No.:** **US D1,057,997 S**
(45) **Date of Patent:** **** Jan. 14, 2025**

(54) **LATTICE**

(71) Applicant: **Rodney Peter Lynch Jones**, Navy
Gardens (BB)

(72) Inventor: **Rodney Peter Lynch Jones**, Navy
Gardens (BB)

(**) Term: **15 Years**

(21) Appl. No.: **29/900,463**

(22) Filed: **Aug. 21, 2023**

Related U.S. Application Data

(63) Continuation-in-part of application No. 29/850,351,
filed on Aug. 18, 2022, now Pat. No. Des. 996,650.

(57) **CLAIM**

The ornamental design for a lattice as shown and described.

DESCRIPTION

FIG. 1 is an isometric view illustrating my design for a lattice;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings are included for purposes of illustrating portions of the boundaries, but form no part of the claimed design.

1 Claim, 4 Drawing Sheets
